CLAIM

We claim the ornamental design for a sealing element for a reciprocating gas compressor valve, as shown and described.

DESCRIPTION

FIG. 1 is an overall perspective view of a sealing element for reciprocating gas compressor valve showing our new design, in condition of use;

FIG. 2 is an overall exploded view of the sealing element for reciprocating gas compressor valve;

FIG. 3 is an overall top view thereof, in condition of use;

FIG. 4 is a cross sectional view of FIG. 3 showing the sealing element for reciprocating gas compressor valve;

FIG. 5 is a top perspective view thereof;

FIG. 6 is a side elevational view thereof;

FIG. 7 is a top view thereof;

FIG. 8 is a bottom view thereof; and,

FIG. 9 is a cross-sectional view thereof.

The broken lines in the drawings are included of the purpose of illustrating environment and form no part of the claimed design.

1 Claim, 5 Drawing Sheets
